F. L. Ewin.

UNITED STATES PATENT OFFICE.

GEORGE W. WASHBURN, OF WEST NEW BRIGHTON, NEW YORK.

SAFETY-CATCH FOR PINS.

SPECIFICATION forming part of Letters Patent No. 252,159, dated January 10, 1882.

Application filed November 22, 1881. (No model.)

To all whom it may concern:

Be it known that I, GEORGE W. WASHBURN, a citizen of the United States, residing at West New Brighton, in the State of New York, have 5 invented a new and useful Improvement in Safety-Catches for Pins, of which the following is a specification.

This invention is additional to the improvement in safety-catches for pins described and 10 claimed in my specification forming part of Letters Patent No. 247,228, dated September 20, 1881, and relates more particularly to the construction of a self-holding guard-tube, and its incorporation in a safety-catch of the same 15 general form and mode of operation as those described in my aforesaid previous specification.

The general object of my present invention is to form a light and secure safety-catch adapted to be readily manipulated and applied 20 alike to breastpins and other jewels having pin-tongues, and to nursery-pins or protection-pins, and to pins the bars or bodies of which will not accommodate a supplemental support for the outer tube of my telescopic attachment, and those in which spring-tongues 25 and stop-hinges are not used, as well as others.

To this end I provide my improved safety-catch with a guard-tube adapted to expand within the outer tube, so as to securely hold it 30 self in its different positions without sustaining any pressure from the pin-tongue, the pressure of the latter being sustained by the scroll-catch, which is readily made of the requisite strength to support the outer tube also 35 without assistance, while the self-holding guard-tube slides more smoothly than an unyielding one, is more easily fitted, and is readily manufactured in a neat and ornamental form, as hereinafter more fully set forth.

40 Figures 1 and 2 of the accompanying drawings are perspective views of a magnified illustrative pin provided with this safety-catch, showing it respectively open or unlocked and closed or locked. Figs. 3 and 4 are similar 45 perspective views, on a still larger scale, of the safety-catch alone. Fig. 5 represents a longitudinal section through the outer parts of the safety-catch, as shown in Fig. 3, showing the guard-tube in elevation with dotted outlines 50 of adjoining parts; and Fig. 6 a longitudinal section in the same plane through the safety-

catch as shown in Fig. 4, with dotted outlines, as in Fig. 5, showing the pin-point within the guard-tube, and Fig. 7 is a perspective view of the guard-tube alone. 55

Like letters of reference indicate corresponding parts in all the figures.

B may represent a longitudinal or transverse bar or the body or back plate, and P the attaching-pin or tongue of a breastpin, for example; h, an ordinary stop-hinge uniting these parts, and c an ordinary scroll-catch.

The other parts of my improved safety-catch are a fixed cylindrical tube, t, termed the "outer tube," which is preferably soldered to one 65 side of said scroll-catch, so as to project outwardly therefrom in line with the catched pin P, and inner tube or thimble, g, termed the "guard-tube," sliding longitudinally within said outer tube, and having an open inner 70 end to receive and inclose the point of the pin, with or without a supplemental support, b, at the outer end of the outer tube, in the form of a connecting-bar. To adapt said guard-tube g to expand within said outer tube, so as to 75 hold itself in different positions, it has been made as follows: Two half-tubes, 1 2, Fig. 7, of proper size, are united at one end by slipping a ring, 3, over them. They are then sprung apart at the opposite end, and in this 80 condition are soldered to said ring, a "shot," 4, to form a retracting-knob, being attached in like manner and at the same operation to the same end of the guard-tube, which is its outer end. The half-tube 1, having been cut longer 85 for the purpose, is so shaped at its free end as to form a projection, 5, adapted to be bent up, as shown in dotted lines, and in this shape to work as a stop in a longitudinal opening, 6, in the back of the outer tube, t, and to close nearly 90 into or against the scroll-catch c, as shown in Figs. 3 and 4. After the united scroll-catch and outer tube have been attached, and these parts of the safety-catch, Figs. 3 and 4, have been otherwise finished and polished, the other 95wise finished guard-tube, in the form represented by full lines in Fig. 7, is united therewith by pressing the two half-tubes together and inserting the open end into the outer end of said outer tube, and, finally, bending up 100 the stop-projection 5. The half-tubes tend by sufficient elasticity to regain their separated

condition, and consequently act, by an efficient outward pressure within the outer tube, to hold the guard-tube frictionally in its different positions, as aforesaid, without sustaining the 5 pressure of the pin, which is preferably borne solely by the scroll-catch, as illustrated by dotted lines in Fig. 6. The said opening 6 in the back of the outer tube is formed in line with the opening of the scroll-catch, and serves 10 to admit the point of the pin P and to release the same, while it is inconspicuous and is not subjected to wear by the pin. The retraction of the guard-tube is limited by said stop-projection 5, and its inward movement is limited 15 by said ring 3 in the example. The safety-catch alone, in two parts, c t and g, may be furnished by the manufacturers to the trade, to be attached by the latter.

The scroll-catch c may be readily made and 20 attached so as to afford ample support to the outer tube without the aid of the bar b. When this cannot be conveniently used a shot may take the place of the bar b, an eye-ring or the like may be substituted for the shot 4 to provide 25 for retracting the guard-tube by means of a pin-point, and other like modifications which will suggest themselves to those skilled in the art may be made at will without departing from the present invention. An inelastic pin 30 and a hinge without a stop may be used, and the self-holding guard-tube may be produced in other ways than by the method herein specified, for the purposes of this invention.

The several parts may be made of any suitable metal.

I do not claim, broadly, a safety-catch for pins having or adapted to have a single connection with the bar or body of the pin or jewel, as I am aware that safety-catches de-

signed for use alone or without a scroll-catch 40 have been so attached; neither do I claim a self-holding inner tube in a safety-catch so broadly as to include an inner tube in the form of a screw, which is old. My self-holding inner tube expands with an elastic pressure 45 within a fixed outer tube and slides longitudinally without rotating.

Having thus described my said improvement, I claim as new—

1. A safety-catch for pins having a guard-tube adapted to slide longitudinally within an outer tube to inclose the point of the pin and to release the same, and adapted to expand within said outer tube to hold itself in its different positions, substantially as herein specified. 55

2. The combination, in a safety-catch for pins, of a fixed scroll-catch adapted to sustain the pressure of the pin, an outer tube fixedly attached to said scroll catch, and having an opening in its back corresponding with the opening of said scroll-catch to receive the point of the pin, and a guard-tube adapted to slide longitudinally within said outer tube to inclose the point of the pin and to release the same, 60 and adapted to expand within said outer tube to hold itself in its different positions, substantially as herein specified. 65

3. In a safety-catch for pins, a self-holding guard-tube composed of two half-tubes with an embracing-ring and a terminal shot at one end united therewith, said half-tubes being sprung apart at their free ends, as herein described, for the purposes set forth. 70
